UNITED STATES PATENT OFFICE.

WILLIAM RENNIE, OF TISHOMINGO, INDIAN TERRITORY.

DESIGN FOR A VEHICLE-STEP.

SPECIFICATION forming part of Design No. 27,390, dated July 20, 1897.

Application filed June 18, 1897. Serial No. 641,362. Term of patent 14 years.

To all whom it may concern:

Be it known that I, WILLIAM RENNIE, of Tishomingo, Chickasaw Nation, Indian Territory, have invented and produced a new and original Design for a Vehicle-Step, of which the following is a full, clear, and exact description.

The leading feature of the design consists in an arm the upper end of which is bent over at an angle thereto, the lower end bent up in an opposite direction to the upper end, and the portion between said upper and lower ends having a rounded projection.

In the drawing a perspective view of a vehicle-step embodying my new design is shown.

The design in its entirety comprises an arm

or body A, the central portion of which is rectangular in cross-section and provided with a rounded projection B, the upper portion being rounded at C and bent over at an angle to the body and terminating in a rounded projection D and bent up in the opposite direction to the upper portion and terminating in an enlarged flat portion E.

25

I claim—

The design for a vehicle-step, substantially as herein shown and described.

WILLIAM RENNIE.
